SELF-DESTRUCTION FUZE

Frank B. Wallace, Phoenix, Ariz.

Application September 14, 1944, Serial No. 554,140

3 Claims. (Cl. 102—71)

(Granted under the act of March 3, 1883, as
amended April 30, 1928; 370 O. G. 757)

1

The invention described herein may be manufactured and used by or for the Government for governmental purposes without the payment to me of any royalty thereon.

This invention relates to fuzes for projectiles.

An object of the invention is to provide a fuze which insures the self destruction of the projectile after it has traveled a predetermined time or distance without having first been exploded by contact with a target.

Another object of the invention is to provide a fuze which is so compact that it may be used in the smaller sizes of projectiles in which little space is available for this purpose.

Further objects will appear from the following description.

Where projectiles are fired at a target such as an airplane, and are designed to be exploded upon striking the target, those projectiles which miss the target will fall to the ground and explode on contact therewith, causing possible damage to friendly personnel and property. It therefore becomes necessary to equip the projectile with a detonating device in addition to the percussion fuze, so that the projectile, having missed the target, will explode before hitting the ground. This may take any one of several forms, and the present invention is believed to describe an effective method.

A typical fuze according to the invention is illustrated in the drawings, in which:

Figure 1 is a longitudinal sectional view of the fuze,

Figure 2 is a vertical sectional view of the fuze along the lines A—B,

Figure 3 is a perspective view of the detent 11, and

Figure 4 is a plan view of a blank from which detent 11 may be formed.

Reference to the drawings shows a fuze body 1 having a longitudinal chamber, formed by concentric cylindrical bores of various diameters as shown. In the nose end of the chamber is placed a closing disk 2 fastened by crimping or other suitable means and at the tail end is a separable lower disk 3 provided with a central bore 22. The magazine 21 contains an annular recess 20 in which is placed a sensitive primer or percussion cap. The fuze as thus far described is adapted to fire the primer upon contact with a target and thus detonate a powder train in the shell, causing it to explode. If the shell does not hit a target, then it is still made to explode before hitting the ground by means of the rest of the construction shown.

2

The chamber in the fuze body between the closing disk 2 and the lower disk 3 contains a longitudinally mounted firing pin 5. The firing pin 5 has one end suitably rounded or pointed, and is 5 slidably positioned so that its unpointed end is inserted into the cylindrical recess 19 in the closing disk 2, while its pointed end is inserted through the bore 22 in the lower disk 3 with the pointed end a short distance from the primer. A 10 coiled spring 7 presses against a collar 18 on the firing pin 5, thus urging the firing pin toward the primer 24 in the recess 20. A detent 11 resting against the lower disk 3 holds back the collar 18 thus preventing the firing pin 5 from contacting and exploding the primer 24. The shape 15 of the detent 11 may also be seen in Fig. 3. Detent 11 is provided with a bent leaf spring 10 fastened to it by means of a rivet 12 and the spring, with one leg bearing against the side 20 of the firing pin 5, tends to urge the end of detent 11 adjacent to collar 18 outwardly so that if the detent were not prevented from such movement said end would move to a position clear of collar 18, allowing the spring 7 to push the collar and 25 hence the firing pin 5 toward the primer 24, detonating it and exploding the projectile.

However, this is prevented by the stop 14 which here takes the form of an annular washer made of a material which while dry has considerable 30 strength but which becomes flaccid when made wet by a liquid. A spacing washer 15 separates stop 14 from the lower disk 3. The washer 14 may be of paperboard, cardboard, or similar substance and the wetting liquid water. The dimensions of the washer 14 will depend on the speed 35 with which it is weakened by the action of the wetting liquid and the time at which the shell is to explode after missing the target. The washer 14 may also be of celluloid or other similar material and the liquid a suitable solvent such as acetone. Or an acid liquid may be used with a washer of a material easily weakened by the acid. It is seen that there are many well known combinations of washer material and liquid 40 that may be employed to achieve the desired result. The liquid 26 is stored within an annular hollow frangible capsule 6 made of clear glass or other similar material, and positioned within the fuze as shown, its outside diameter 45 being such that it fits snugly into the chamber, and its inside diameter large enough to clear the other parts of the fuze adjacent to it. The capsule 6 rests against a felt washer 8 and is held in position by a coiled spring 9 which in turn 50 rests on the projection of washer 14 substantially 55

as shown. It will be noted that the capsule 6 may be made of any one of a number of materials having the desired properties. One of these is clear glass which is easily shattered when the shell is fired, quickly releasing the liquid, and also permits visual inspection before assembly to ascertain the quantity of the contents. Plastic or gelatinous substances can also be used with those liquids that do not dissolve them, provided the walls are thin enough to break when the shell is fired. While the force of setback on firing is normally sufficient to break the capsule 6, a sharp pointed projection may be mounted on each of the weights 13 at the location 27, the points being long enough and so directed as to engage and cut open the capsule 6 upon setback. This may be done by changing the outline of the blank shown in Fig. 4 to make the angle at 27 acute. The detent 11 is also provided with a bore 17 substantially greater in diameter than the firing pin 5, and the edge 16 of the bore 17 is rounded off to prevent binding between the detent 11 and the firing pin at the point of contact. The bore 17 may be formed by drilling two overlapping holes in the detent 11, so that the lower hole as seen in Fig. 2 is only slightly larger than the firing pin diameter while the upper overlapping hole is considerably larger. The result is that the remaining lower arc of the lower hole forms a bearing surface at this point between the detent 11 and the firing pin 5, the spring 10 serving to keep the detent and firing pin in contact, and prevents sidewise movement of the detent at this point. Weights 13 are attached to the detent 11 to substantially counterbalance centrifugal forces resulting from rotation of the shell during flight due to rifling of the gun barrel. The detent 11 including the weight portions 13 may be stamped and formed from a single piece of sheet metal if desired, as shown in Figs. 3 and 4.

A typical cycle of operation may now be described. The shell is fired from the gun at a target which may be a moving airplane. If the shell hits the target, the concussion resulting from impact is transmitted through the fuze to the primer, causing the shell to explode. It should be noted that the severe setback resulting at the time the gun is fired, is normally sufficient to break the liquid containing frangible capsule 6 through the force of inertia, causing the liquid to escape from the capsule and to soak the washer 14. The washer 14 weakens or becomes flaccid under the effect of the wetting and by the time the shell has passed the target and is falling to earth the washer has been so weakened that it interposes little or no resistance to the end 25 of the detent 11, and the spring 10 together with any unbalanced centrifugal force, forces the end 23 of the detent 11 outwardly so that it clears the collar 18 which is then pushed axially by the spring 7, forcing the firing pin 5 against the primer, detonating it and thus exploding the shell in the air before it reaches the ground.

While the description shows a preferred form

of the invention it is to be understood that numerous changes in the shape, size, materials and arrangement may be resorted to without departing from the spirit and scope of the invention as claimed hereinafter.

I claim:

1. A self destruction fuze for projectiles, comprising a primer, a spring actuated firing pin to detonate said primer, a detent normally holding said firing pin retracted, a stop normally holding said detent in place, said stop capable of becoming flaccid upon absorption of a liquid, spring means between said firing pin and said detent for biasing the same away from said firing pin and against said stop, a liquid for making said stop flaccid whereby said spring means becomes operative to move said detent away from said firing pin to release the same for movement, a frangible container for said liquid, projecting means on said detent adapted to strike said frangible container on set back of same to break the same for releasing the liquid therein for contact with said stop.
2. A fuze for projectiles, comprising a primer, a spring pressed firing pin for exploding said primer, and having a collar; an L-shaped detent for normally holding said firing pin retracted by bearing against said collar, said detent having an aperture through its base through which the lower portion of the firing pin passes and of substantially larger diameter than said portion of the firing pin; a leaf spring mounted on said detent and urging it radially outward from the axis of said firing pin; weights mounted on the base of said detent to counter balance the centrifugal forces of rotation; a stop holding said detent against the collar on said firing pin, said stop capable of becoming flaccid upon absorption of a liquid; a liquid for wetting said fibre stop to cause it to become flaccid; an annular frangible container for said liquid; and inertia operated means for freeing said liquid from said container and bringing it into contact with said soluble fibre stop.
3. A fuze according to claim 2 in which the inertia operated means consists of sharp projections mounted on the counter weights on said detent against which the frangible container is broken by force of inertia upon setback.
